CHARLES C. ABBOTT, OF PITTSFIELD, MASSACHUSETTS, ASSIGNOR TO TRIUMPH VOTING MACHINE COMPANY, OF PITTSFIELD, MASSACHUSETTS, A CORPORATION OF NEW JERSEY.

COUNTER OPERATING AND LOCKING MECHANISM FOR VOTING-MACHINES.

No. 881,991.

Specification of Letters Patent. Patented March 17, 1908.

Application filed May 20, 1907. Serial No. 374,610.

To all whom it may concern:

Be it known that I, CHARLES C. ABBOTT, a citizen of the United States, residing at Pittsfield, county of Berkshire, State of Massachusetts, have invented a new and useful Counter Operating and Locking Mechanism for Voting-Machines, of which the following is a specification.

This invention relates to the counting mechanism of voting machines.

It is one of the objects of the invention to provide improved mechanism for connecting actuated voting members with the corresponding counters and for operating the counters.

A further object of the invention is to provide simple and reliable mechanism that will insure the counters against injury, from being tampered with and against improper actuation either forward or backward.

With these and other objects in view the invention consists in certain constructions and in certain parts, improvements and combinations which will be hereinafter described and then specifically pointed out in the claims hereunto appended.

In the accompanying drawings forming a part of this specification, in which like characters of reference indicate the same parts in all of the figures, Figure 1 is a rear elevation of a portion of a voting machine, the doors being removed, illustrating a form of my novel counter-operating and locking mechanism in which the countershafts and counter-pins are normally in vertical alinement, the counter-dogs being shown as made from sheet metal and a portion of the counter-dogs being shown in the engaged or voting position; Fig. 2 a detail elevation on an enlarged scale, illustrating a portion of a counter-bar with two counters attached and the corresponding voting member shafts and counter-dogs, the upper counter-dog being in the engaged or voting position and the lower counter-dog being in the normal or disengaged position; Fig. 3 a similar view, the counter-bar having been moved far enough as in the operation of counting to impart to the engaged—*i. e.*, the upper counter—a quarter rotation; Fig. 4 a similar view, the movement of the counter-bar having proceeded far enough to impart a half rotation to the engaged counter; Fig. 5 a similar view, the movement of the counter-bar having proceeded far enough to impart a

three-quarter rotation to the engaged counter; Fig. 6 a perspective, illustrating a form of counter locking bar adapted for attachment to a standard and provided with locking fingers having notches to receive the counter operating-pin; Fig. 7 a perspective, illustrating a form of counter locking bar having a web formed integral therewith and provided with openings to receive the counter operating pin; Fig. 8 a side elevation of a sheet metal counter-dog detached; Fig. 9 a front elevation of a sheet metal counter-dog detached, that is, an elevation from a point of view the reverse of the point of view in Fig. 1; Fig. 10 an edge view of a counter-dog retaining spring detached; Fig. 11 an elevation of a counter-dog retaining spring detached; Fig. 12 an elevation on an enlarged scale of a counter operating disk, illustrating my novel movable counter-operating pin; Fig. 13 a similar view with the housing removed; Fig. 14 an edge view of the counter operating disk as seen from the top in Fig. 12; Fig. 15 a view similar to Fig. 1, illustrating a form of the invention in which the countershafts and counter-operating pins are normally in horizontal alinement, and showing a variant form of counter-dogs, a portion of the counter-dogs being shown in the engaged or voting position; Fig. 16 a detail elevation on an enlarged scale corresponding with Fig. 15, illustrating a portion of a counter-bar with two counters attached and the corresponding voting member shafts and counter-dogs, the upper counter-dog being in the engaged or voting position and the lower counter-dog being in the normal or disengaged position; Fig. 17 a similar view, the counter-bar having been moved far enough as in the operation of counting to impart to the engaged—*i. e.*, the upper counter—a quarter rotation; Fig. 18 a similar view, the movement of the counter-bar having proceeded far enough to impart a half rotation to the engaged counter; Fig. 19 a similar view, the movement of the counter-bar having proceeded far enough to impart a three-quarter rotation to the engaged counter; Fig. 20 a view corresponding with Figs. 6 and 7, illustrating a form of counter locking bar having a web formed integral therewith and provided with notches in its edge for engagement by the counter operating pin; Fig. 21 a side elevation of a form of counter

dog shown in Figs. 15 to 19, inclusive, detached; and Fig. 22 is a front elevation corresponding therewith, that is, an elevation as seen from a point of view the reverse of the point of view in Fig. 15.

20 indicates the base of a voting machine, in the present instance the Triumph voting machine, 21 the top plate, 22 standards, 23 the voting member shafts and 24 the voting levers which appear in dotted lines only. In the form illustrated in Figs. 1 to 5, inclusive, and 8 and 9, the counter-dogs, indicated by 25, are made from strips of sheet metal bent to substantially U-shape. The 15 counter operating pins engage the counter-dogs by passing between the arms at their intersection, as at 47, when the dogs are moved to the engaging position. Voting member shafts 23 are provided with flat-tened or angular portions 26 and the arms of the counter-dogs, which are indicated specifically by *a* and *b*, are provided with correspondingly shaped holes 27 to receive the angular portions which act to retain the 20 counter-dogs against rotation on the shafts. The counter-dogs are held against longitudinal movement on the voting member shafts by means of pins 28, which are driven into holes in said shafts, one pin lying on the 25 outer side of arm *b* and one on the inner side of arm *a*. The arm *a* of each counter-dog is provided at its attached end with grooves or depressions 29 and 30. These grooves or depressions lie at an angle to each other and 30 diametrically to the hole 27 in said arm. 35 31 denote bow-springs having at their ends recesses 32 which receive the voting member shafts and cross ribs 33 which are adapted to engage the grooves 29 and 30 in the counter-dogs. The function of these springs is to hold the counter-dogs in either the engaged or the disengaged position and with them the voting members in either the voting or non-voting position. When a rib 33 on a spring 40 45 is in engagement with a groove 30 on a counter-dog, the dog will be held in the normal or disengaged position, and when the rib is in engagement with groove 29 the dog will be held in the operative or engaged position. See, for example, the upper counters in Figs. 2 to 5, inclusive, and the upper counter in the left hand column in Fig. 1. The mid-length of each spring bears against a standard and each spring acts to retain 50 55 two counter-dogs either in the engaged or disengaged position as may be required. It will be noted that the springs are self-retaining in place and also coöperate with the pins 28 to retain the counter-dogs in place on the voting member shafts.

In the form illustrated in Figs. 15 to 19, inclusive, the counter-dogs, indicated by 48, are cast or forged solid. These counter-dogs are shown as provided with heads 49 having holes 50 through them to receive

the voting member shafts and as secured to said shafts by means of pins 51 which pass through the heads and the shafts. The engaging ends of the counter-dogs are shown as bent at an angle as at 52 and as provided 70 with counter-sunk holes 53 to receive the counter operating pins. The counter-dogs are provided with grooves 29 and 30 which lie at an angle to each other and diametrically to holes 50 and are adapted to be engaged 75 by cross ribs 33 on the bow-springs 31 to hold them either in the engaged or operative or in the normal or disengaged position the same as in the other form.

34 denotes counters which are rigidly secured in vertical columns to counter-bars 35. Each counter is provided with a shaft 36, one end of which extends beyond the case and carries an operating disk 37. Each disk carries a housing 38 which is shown as secured 80 thereto by means of lugs formed on the edges thereof and engaging openings 54 formed in the disks, the lugs being headed down on the backs of the disks as at 55 (see Fig. 14).

56 denotes the counter operating pins 90 which are movable in the plane of rotation of the countershafts for a purpose presently to be explained. Each operating pin extends through a curved slot 57 in the housing and is provided with an angular base 58 which 95 lies between the disk and the housing and retains the pin in an upright position while permitting it to slide in the slot should movement of the pin be necessary. The operating pins are preferably made cone-pointed, 100 as shown, to insure the engagement therewith of the corresponding counter-dogs when the latter are moved to the engaging position. See, for example, the upper counters in Figs. 2 to 5 and 16 to 19, inclusive, 105 and certain engaged counter-dogs in Figs. 1 and 15.

The counter-bars are provided with bearings 39 which are mounted on eccentrics 40 carried by shafts 41 journaled in bearings 42 110 upon the standards. Motion is imparted to these shafts to operate the counter-bars and actuate the engaged counters by mechanism which forms no portion of the present invention. It is sufficient for the purposes of this 115 specification to say that after the completion of a voting operation, the voter operates exit mechanism, forming no portion of the present invention, which imparts to the shafts forward rotation and then a backward or return rotation, the effect of which is to cause the counter-bars to make an endwise and lateral rotary oscillation in the vertical plane and then a return oscillation to their normal 120 position. The first movement of the counter-bars causes the engaged counters to rotate bodily about the counter operating pins 56 as centers of rotation and consequently rotates the countershafts 36 and 125 causes a count to be registered by each en- 130

gaged counter. Near the end of the first movement—that is, near the end of the forward rotation of the counter-bars, for example, when three-fourths, more or less, of 5 said forward rotation of the counter-bars and consequent rotation of engaged countershafts has taken place—suitable disengaging mechanism (not shown, as it forms no portion of the present invention) is operated by 10 the exit mechanism to disengage the engaged counters and return the voting member shafts, voting levers and counter-dogs to their normal or disengaged position, as, for example, the lower counters in Figs. 2 to 5 15 and 16 to 19, inclusive. (See also disengaged counters in Figs. 1 and 15.)

Another and vitally important feature of the present invention is that the counters are at all times, except necessarily in the resetting position, presently to be described, locked against the possibility of uncounting or unwarranted counting, in fact, against any 20 operation except the regular counting operation, which can only be performed by complete bodily rotation of each counter about its operating pin when the latter is engaged by a counter-dog. This counter locking operation I effect by means of counter locking bars 43 provided with means for engagement 25 by the operating pins of engaged counters. The counter locking bars are secured to the standards by means of screws passing through holes 44 in said bars. In the form illustrated in Figs. 2 to 6, inclusive, the 30 counter locking bars are shown as provided with fingers 45, each finger being preferably, although not necessarily, provided with a notch 46 which receives the operating pin 56 of the corresponding counter. It will be 35 noted (see the upper line in Figs. 2 to 5, inclusive) that the operating pins of engaged counters are at all times in engagement or approximately so with the fingers 45, and as shown in the drawings, lie in the notches 46 40 in said fingers. In other words, the operating pin of each engaged counter is locked during three-fourths, more or less, of the counting operation between a counter-dog and the corresponding locking finger, and 45 when released by the counter locking dog is held against backward movement by the locking finger. The operating pins of disengaged counters are at all times, except 50 during the counting operation, at their lowest position and lie in engagement or approximately so with the locking fingers, so that movement of the countershafts in either direction is impossible. During the counting 55 operation there is but one portion of the movement of the counter-bars at which the operating pins of disengaged counters are carried far enough away from the locking fingers to permit even a half rotation of the countershafts. It will, of course, be obvious 60 that there must be one disengaged posi-

tion of the counters at which they may be operated, otherwise the counters could not be re-set after an election. This resetting position is illustrated by the lower counters in Figs. 4 and 18. At this position of the parts 70 the counter-bars have made one-half of the counting movement and disengaged counters may be operated, as the operating pins are farthest away from the counter locking bars and will pass the engaging portions 75 thereof, which at all other times act as stops to prevent rotation of the countershafts in either direction.

Another function of the engaging portions of the counter locking bars, is to insure a 80 complete rotation of the countershaft of each engaged counter and therefore insure that each vote cast is accurately counted. It has already been stated that the engaged 85 counter-dogs are disengaged from the operating pins at the completion of three-fourths, more or less, of the rotation of the eccentric shafts. When this disengagement takes place the rotation of the countershafts will be completed through the engagement of the 90 operating pins with the locking fingers, as clearly shown by the lower counter in Fig. 2. Should friction of the counter mechanism retard the free operation of the countershafts so that the operating pins would not return 95 to their normal position when disengaged, this would be wholly immaterial, as the disengaged operating pins, if they did not drop by gravity, would engage the locking fingers and the rotation of the countershafts would 100 be complete by such engagement, thus insuring the count.

In the form illustrated in Fig. 7, the counter locking bars 43 are shown as provided with webs 59 in lieu of fingers, the webs being 105 provided with openings 60 which receive the operating pins. In connection with the forms of counter locking bars illustrated in Figs. 6 and 7, the counters are so arranged 110 that the countershafts and counter-pins are normally in vertical alinement, as in Figs. 1 to 5, inclusive. In the form illustrated in Figs. 15 to 19, inclusive, the counters are so arranged that the countershafts and operating pins are normally in horizontal alinement. 115 In connection with this form, the counter locking bars 43 are provided with webs 59, preferably provided with notches 61 in their edges (see Fig. 20) which receive the operating pins the same as in the other form. In each of these forms the co-operation of the operating pins, counter-dogs and counter locking bars is substantially the same, the engaging portions of the counter locking bars insuring the completion of the 120 rotation of the countershafts after the disengagement of engaged counter-dogs. By making the operating pins 56 movable in the plane of rotation of the countershafts, I 125 avoid the possibility of injury to the counters 130

through engagement of the operating pins with the engaging portions of the counter locking bars should an attempt be made to uncount or to run up any of the counters by tampering with the machine. It will be noted from the upper counters in Figs. 3 to 5 and 17 to 19, inclusive, that in normal counting the relative position of the operating pins 56 in the curved slots 57 does not change. Should tampering be attempted by disengaging any of the counter-dogs during the counting movement and should the operating pins contact with the engaging portions of the counter locking bars when the operating pins and countershafts were in alinement, the operating pins would move inward in the slots in the housings, no injury would happen to the counters or to the machine and both uncounting and unwarranted counting would be prevented.

The operation of my novel mechanism has been so fully described in describing the construction and operation of the parts that further description can hardly be required. It is sufficient to say that in performing the voting operation the voter oscillates voting member shafts which places the counter-dogs carried by said shafts in engagement with the operating pins of the corresponding counters. When the counter-bars are operated in the manner described, each engaged counter is caused to make a complete bodily rotation about its operating pin which is held by the counter-dog. At the end of the counting operation all operating pins, whether previously engaged or disengaged, are brought into engagement with the engaging portions of the counter locking bars so that any movement of a countershaft either to count or uncount is made impossible. During the counting operation these locking fingers make tampering with disengaged counters, except at the resetting position, impossible, as they prevent even a half rotation of the countershafts being made in either direction. I thus insure that no count can be made except upon engaged counters and then only by complete rotation of each engaged counter about its operating pin as a center of rotation.

Having thus described my invention, I claim:

1. In a voting machine, the combination with voting members having counter-dogs and counters having operating pins which are engaged, held and then released by the counter-dogs of actuated voting members, of counter-bars by which the counters are carried, means for imparting endwise and lateral rotary oscillation to the counter-bars to count votes and counter locking bars provided with means for engagement by the operating pins to lock the counters against unwarranted actuation.

2. In a voting machine, the combination

with voting members having counter-dogs and counters having operating pins out of alinement with the counter shafts which are adapted to be engaged by the corresponding counter-dogs, of means for imparting endwise and lateral rotary oscillation to the counters and counter locking bars provided with means for engagement by the operating pins to lock the counters against unwarranted actuation.

3. In a voting machine, the combination with voting members, having counter-dogs and counters having operating pins which are adapted to be engaged by the corresponding counter-dogs, of means for imparting endwise and lateral rotary oscillation to the counters, and means for locking disengaged counters against actuation.

4. In a voting machine, the combination with voting members, having counter-dogs and counters having operating pins which are adapted to be engaged by the corresponding counter-dogs, of means for imparting endwise and lateral rotary oscillation to the counters, and counter locking bars provided with means for engagement by the operating pins to lock the counters against unwarranted actuation.

5. In a voting machine, the combination with voting members, having counter-dogs and counters having operating pins which are adapted to be engaged by the corresponding counter-dogs, of means for imparting endwise and lateral rotary oscillation to the counters, and counter locking bars provided with notches which are engaged by the operating pins to lock the counters, substantially as described, for the purpose specified.

6. In a voting machine, the combination with voting members having counter-dogs provided with grooves at an angle to each other, of springs having cross ribs engaging said grooves to hold the counter-dogs in the engaged or disengaged position.

7. In a voting machine, the combination with voting members having counter-dogs provided in one side with grooves at an angle to each other, of a bow-spring having at its ends recesses to receive voting member shafts and cross ribs engaging said grooves to hold either counter-dog in the engaged or disengaged position and the voting member in the voting or non-voting position.

8. The combination with a voting member shaft having an angular portion and a counter-dog formed from a strip of sheet metal bent to U-shape and having a hole corresponding with the shaft, one side of said dog being provided with grooves at an angle to each other, of a spring having in its end a recess to receive the voting member shaft and a cross rib adapted to engage the grooves in the counter-dog, substantially as described, for the purpose specified.

9. The combination with a voting member

shaft having an angular portion, a counter-dog formed from a strip of sheet metal bent to U-shape and having in its ends holes corresponding with the angular portion of the shaft, one side of said dog being provided with grooves at an angle to each other and pins engaging the shaft to hold the dog in place, of a spring having a rib adapted to engage the grooves in the counter-dog, substantially as described, for the purpose specified.

10. In a voting machine, the combination with a voting member shaft and a counter-dog formed from a strip of sheet metal bent to U-shape and secured to the shaft, said dog being provided in one side with grooves at an angle to each other, of a counter having an operating pin adapted to engage the dog by passing between the arms when the dog is moved to the engaging position, and a spring 20 having a rib adapted to engage the grooves to lock the dog in the engaged or disengaged position.

11. The counter-dog 25 formed from a strip of sheet metal bent to U-shape and having in one side grooves at an angle to each other, substantially as described, for the purpose specified.

12. In a voting machine, the combination with a voting member having a counter-dog, 30 of a counter having a slidable operating pin which is engaged by the counter-dog at each voting operation, means for imparting endwise and lateral oscillation to the counter and means for locking the counter against 35 actuation when disengaged.

13. In a voting machine, the combination with a voting member having counter-engaging means, of a counter having a relatively movable shaft and an operating pin adapted 40 to be engaged by the voting member and yieldingly mounted to move independently of said shaft, substantially as described, for the purpose specified.

14. In a voting machine, the combination 45 with a voting member having a counter-dog, of a counter having a shaft carrying a disk and an operating pin carried by the disk and adapted to be engaged by the dog, said pin being movable relatively to the disk, substantially as described, for the purpose specified.

15. In a voting machine, the combination 50 with a voting member having a counter-dog, of a counter having a shaft carrying a disk provided with a housing having a slot and an operating pin extending through the slot and having an angular base lying under the housing, said pin being adapted to be engaged by the counter-dog and being movable in the slot, substantially as described, for the purpose specified.

16. In a voting machine, the combination 55 with a voting member having a counter-dog, of a counter having a shaft carrying a disk provided with a housing having a slot, an op-

erating pin extending through the slot and 65 having an angular base lying under the housing, said pin being adapted to be engaged by the dog and a counter locking bar which is engaged by the pin to lock the counter against unwarranted actuation, the operating pin moving backward in the slot should 70 said pin contact with the counter locking bar when the operating pin and countershaft were in alinement.

17. In a voting machine, the combination 75 with voting members having counter-dogs and counters having operating pins which are engaged, held and then released by the counter-dogs of actuated voting members, of means for imparting endwise and lateral rotary oscillation to the counters to actuate engaged counters and counter locking bars having means for engagement by the operating pins after the counter-dogs are disengaged therefrom to insure the return of the operating pins to their normal position after an actuation.

18. In a voting machine, the combination with voting members having counter-dogs and counters having movable operating pins, 90 of means for imparting endwise and lateral rotary oscillation to the counters for the purpose set forth, and counter locking bars having means for engagement by the operating pins, said pins moving backward should they 95 engage the counter locking bar when the operating pin and countershaft were in alinement.

19. In a voting machine, the combination 100 with a voting member having a counter-dog and a counter having a shaft provided with a slotted housing and an operating pin extending through the slot and having a base lying under the housing, of a counter locking bar having means for engagement by said pin, 105 the pin moving backward in the slot and preventing breakage should it engage the counter locking bar when the pin and the shaft were in alinement.

20. In a voting machine, the combination 110 with voting members having counter-dogs and counters having operating pins which are engaged, held and then released by the counter-dogs of actuated voting members, of means for imparting endwise and lateral rotary oscillation to the counters, for the purpose set forth, and means engaged by the operating pins for insuring the return of disengaged operating pins to the normal position 115 after the actuation of the counters.

21. In a voting machine, the combination 120 with voting members having counter-dogs and counters having operating pins which are engaged, held and then released by the counter-dogs of actuated voting members, of 125 means for imparting endwise and lateral rotary oscillation to the counters, for the purpose set forth, and fixed counter locking bars

having means for engagement by the counter-pins, substantially as described, for the purpose specified.

22. In a voting machine, the combination with counters having shafts and operating pins movable relatively to the shafts, for the purpose set forth, of means for imparting endwise and lateral rotary oscillation to the counters and fixed counter locking bars having means for engagement by the operating pins.

23. In a voting machine, the combination with counters having shafts, disks carried by said shafts, housings secured to the disks and provided with slots and operating pins extending through said slots and having bases within the housings, of means for imparting endwise and lateral rotary oscillation to the counters, and counter locking bars having means for engagement by the operating pins.

24. In a voting machine, the combination with counters having shafts, disks carried by the shafts, housings secured to the disks provided with curved slots, and operating pins extending through the slots and having angular bases lying under the housings, of means for imparting endwise and lateral ro-

30
tary oscillation to the counters, and counter locking bars having means for engagement by the operating pins.

25. In a voting machine, the combination with a voting member having counter-engaging means, of a counter having a relatively movable shaft, and an operating pin adapted to be engaged by the voting member and movable in a plane at right angles to the axis of the counter shaft, substantially as described, for the purpose specified.

26. In a voting machine, the combination with a voting member having counter-engaging means, of a counter having a relatively movable counter shaft to actuate said counter and an operating pin carried by said shaft and adjustable relatively to said shaft and independently of the actuating movement of said shaft, said pin being engaged by the voting member when in the voting position.

In testimony whereof I affix my signature, in presence of two witnesses.

CHARLES C. ABBOTT.
